ELECTRIC SWITCH.

1,180,208.

Specification of Letters Patent. Patented Apr. 18, 1916.

Application filed March 6, 1913. Serial No. 752,481.

To all whom it may concern:

Be it known that we, GEORGE B. THOMAS and ERIC ANDERSON, both citizens of the United States of America, and residing at 5 Bridgeport, in the county of Fairfield and State of Connecticut, have invented a certain new and Improved Electric Switch, of which the following is a specification.

Our invention relates to electric switches 10 and particularly to switches designed for use in electric lamp sockets, and the object of our invention is to provide a switch of the general character of that shown in the Clauder Patent 1,055,137 dated March 4, 15 1913, but of simplified and improved construction.

In the accompanying drawings, Figure 1 is a broken vertical section through an electric lamp socket in which our invention 20 is embodied in one form; Fig. 2 is a similar section at right angles thereto and omitting the socket casing and shell terminal; Fig. 3 is a perspective of the switch mechanism; Fig. 4 is a perspective of the switch piece 25 and its sleeve bearing detached; Fig. 5 is a perspective of the detent disk; Fig. 6 is a side elevation of the same; Fig. 7 is a perspective of the switch spindle; Fig. 8 is a perspective of the cam yoke; Fig. 9 is a perspective of one of the switch terminals; Fig. 10 is an end elevation of the switch 30 frame; and Fig. 11 is a side elevation showing the position of the detent lugs about to enter the slots in the stop plate.

The insulating body of the socket may 35 be of any suitable form, that preferred comprising, as here shown, two porcelain buttons A and B suitably recessed on their juxtaposed faces to form in assembled condition a closed switch chamber, and perforated to permit the passage therethrough of the various securing screws. Terminal brackets 10 and 11 extend between the buttons at substantially diametrically opposite 40 points and serve not only to unite the buttons but also to carry the binding screws 12 and 13 for the leading-in wires. The terminal bracket 10 is electrically connected directly to the lamp-receiving shell 14 on the 45 button B by the screw 15. The other terminal bracket 11 carries the spring switch contact 16 which lies in the recess 17 in the switch chamber and leads the current through the switch piece to the opposite 50 spring switch terminal 18 when the switch 55

is "on." Angled wings 19 on the contact 16 form slideways which enable the contact to be readily slid into position and held on the upper end of bracket 11. A screw 20 permanently connects the switch terminal 60 18 with the center lamp contact 21 on the button B.

The switch mechanism is positioned in the switch chamber upon a switch frame 22 which is here shown rigidly held in position by the securing screw 23. This frame comprises at one end of the base, an upstanding bearing lug 24 perforated to permit the switch spindle 25 to pass freely through and journal therein. At the other 65 70 end, a second and larger upstanding lug 26 is formed which is centrally perforated to permit the switch spindle to freely journal therein, and in which are formed four radial recesses or slots 27 for a purpose 75 about to be described.

Freely journaled on the switch spindle 25, is the rotary switch piece comprising contact bars $x-y$ united at opposite ends by webs 28, 29, perforated to permit the 80 passage of the switch spindle therethrough. The perforation 30 in web 28 is of greater diameter than the spindle to permit the adjustment of a bearing sleeve 31 therein, while radial slots 32 opening to the perforation in web 29 are provided to permit the 85 passage therethrough of the fin 33 on the switch spindle during the assembly of the switch parts. Detent lugs 34 extending beyond the face of the web 29 are provided to 90 engage in the radial slots 27 in the frame lug 26 and thus temporarily lock the switch piece in its "on" or "off" position. In the form shown, these lugs are angled over from a disk 35 independent of the switch piece, 95 but pressed against the web 29 by the spring 36 so that the lugs are held in radial slots 37 in the web 29 and the parts are thus rotarily rigid with relation to each other. The end faces of the lugs 34 are preferably 100 oppositely beveled to insure a quick escape-
ment and a certain stop of the switch piece in its several stop positions.

The operating cam 38 for the switch is formed on the perforated web 39 at one end 105 of the yoke piece 40. The web 41 at the other end of the yoke is centrally perforated to form a bearing radially slotted at 42 to receive the fin 33 on the switch spindle. In assembled condition this fin engages in the 110

slots 42 and is of such length that the spindle and cam have sufficient longitudinal play with relation to each other in engaged condition, to permit of the operation of the 5 switch. The opposite ends 43-44 of a coil spring 45 confined on the spindle between opposite ends of the yoke piece 40, straddle the latter and one of the contact bars, viz. x , of the switch piece. The switch spindle 10 is retained in position by a washer 46 which engages the same beyond the end frame lug 24, while the hub 47 of the key 48 bears against the other frame lug 26 thus holding the key spindle against longitudinal displacement.

The operation of the switch is readily understood. Upon the rotation of the spindle 25 in either direction by means of the key 48, the yoke piece 40 engaged by the 20 fin 33 on the spindle, is rotated with the latter, while the switch piece remains stationary by reason of the engagement of the detent lugs 34 in the slots 27 in the end frame lug 26. The rotation of the cam 25 yoke 40 with relation to the switch piece places the coil spring 45 under tension. It also brings the cam 38 into engagement with the web 28 of the switch piece and displaces the latter longitudinally on the switch 30 spindle, thereby compressing the spring 36 against the web 41 of the cam yoke. As soon as the switch piece has been longitudinally displaced far enough to free the detent lugs 34 from the slots 27, in the end 35 frame 26, the spring 45 rotates the switch piece to its next position in which it is halted by the detents 34 which snap into the next pair of radial slots 27 under the influence of the spring 36. During the travel 40 of the detents from one stop position to the next, the switch piece rides down the side of the cam 38 and under the influence of the spring 45 is longitudinally displaced on the switch spindle, returning to its position flush 45 against the end frame. During this movement the disk 35 becomes spaced from the web 29 of the switch piece being held away by the detent lugs 34 which are traveling over the inner face of the end frame 26 between 50 the slots 27. This action is of value in making certain the operation of the stops, since the spring 36 is thereby relieved from the burden of shifting the switch piece back to position and exerts its whole strength 55 upon the disk 35 when the stop lugs of the latter reach the slots 27 in the end frame 26. The opposite bevel of the ends of the stop lugs 34 has the effect of tilting one of the lugs into its slot 27 ahead of the other, since 60 one slides down its beveled end into its slot 27, while the other is still held out by reason of the fact that the crest of its bevel is still in engagement with the flat face of the end frame 26. This action adds further certainty 65 to the function of the detents, since

the one which is tilted down into its slot ahead of the other presents a flat stop face to the edge of the slot 27 and is well down in the slot when engagement takes place.

Various modifications which do not depart from the invention illustratively embodied in the construction described and shown, will readily suggest themselves.

We claim as our invention:

1. An electric switch comprising a rotary switch spindle, a contact piece freely rotating on said spindle, a cam rotating with said spindle, a detent moving with said contact piece, a rigid stop frame for said detent, a switch spring engaging said cam and switch piece and a spring between said cam and detent tending to hold said detent in engagement with said stop frame.

2. In an electric switch, a rotary switch piece and an independent detent moving therewith, a rigid stop plate, a spring tending to keep said detent in engagement with said switch piece and stop plate, in combination with an independent spring for operating the rotary switch piece and a rotary operating member engaged by said switch spring and serving to place the latter under tension.

3. In an electric switch, a rotary switch spindle, a switch piece freely rotatable thereon and having limited freedom of longitudinal displacement thereon, said switch piece comprising contact elements and webs connecting the opposite ends thereof, through which said spindle passes, a cam moving with the spindle and bearing against one end web to displace the switch piece longitudinally on the spindle in one direction, a switch spring engaging said switch piece to rotate the same in either direction and serving on compression to displace said switch piece on the spindle in a direction opposite to that occasioned by the said cam, together with a stop mechanism and an independent spring serving to operate the latter to halt the switch piece after rotation through a quarter turn on the spindle.

4. In an electric switch, a rotary switch spindle, a switch piece freely rotating thereon and comprising contact pieces and webs uniting the ends thereof through which said spindle passes, in combination with a yoke piece comprising connected webs held against rotation on said spindle between the ends of said switch piece, a switch spring mounted on said spindle within said yoke piece and engaging the latter and the switch piece, a cam on said yoke engaging said switch piece to longitudinally displace same on the spindle, detents moving with the switch piece, a stop plate, and a spring between the yoke and detents to press the latter against the stop plate.

5. In an electric switch, contact members

- and a web connecting the same and having 5
guide apertures formed therein, a detent
piece having detent lugs passing through
said guide apertures in the web, spring
means for rotating said contact members in
either direction and a fixed stop plate ad-
jacent said web and apertured to receive
said detent lugs, substantially as described.
6. In an electric switch, a switch spindle
10 rotatable in either direction, a switch spring
tensioned thereby, a rotary switch piece
actuated by said spring, a stop plate having
apertures, and detent lugs moving with said
switch piece and engaging in said apertures
15 to halt the switch piece, said lugs having
their bearing ends beveled in opposite direc-
tions, for the purpose specified.
7. In an electric switch, rotary contact
20 members and a web connecting the same,
said web having guide apertures formed
therein, a detent piece yieldably supported
against said web and having a pair of detent
lugs passing through said guide apertures in
25 the web, a flat stop plate adjacent the web
having apertures in which the detent lugs
engage, said lugs having peripherally ad-
jacent faces serving as stops and bearing
ends on which said detent is supported as
30 it travels between successive stop positions,
said bearing ends being oppositely beveled
to permit one of said lugs to run down in
its aperture in the stop plate on the rotation
of the switch piece in one direction and the
35 other of said lugs to run down in its aper-
ture in the stop plate on the rotation of the
switch piece in the opposite direction.
8. In an electric switch, a radially slotted
stop plate, a switch piece journaled in said
plate and stop lugs moving with said switch
piece and engaging in the slots of said stop 40
plate to halt the switch piece, upon its ro-
tation in either direction.
9. In an electric switch, a switch frame
comprising a base and upstanding end
frames, one of said frames having a bearing 45
aperture and a series of stop apertures radi-
ally arranged with relation to said bearing
aperture in combination with a switch piece
journaled in said plate and stop lugs mov-
ing with said switch piece and engaging in 50
the slots of said stop plate to halt the switch
piece upon its rotation in either direction.
10. In an electric switch, a switch piece
struck from sheet metal and bent to shape,
said switch piece comprising rotary contact 55
bars spaced apart and connected at their
opposite ends by webs lying in parallel
planes at right angles to the plane of the
contact bars, and perforated in register to
receive a switch spindle, one of said webs 60
being radially recessed on opposite sides of
said perforation to receive the lugs of an
independent detent plate.

In testimony whereof we have signed our
names to this specification, in the presence 65
of two subscribing witnesses.

GEORGE B. THOMAS.
ERIC ANDERSON.
